UNITED STATES PATENT OFFICE.

WILLIAM D. SCHUYLER, OF NEW YORK, N. Y.

AUTOMATIC SEAL-TRAP FOR WASH-BASINS AND WATER-CLOSETS.

SPECIFICATION forming part of Letters Patent No. 320,708, dated June 23, 1885.

Application filed June 25, 1883. (No model.)

To all whom it may concern:

Be it known that I, WILLIAM D. SCHUYLER, of the city, county, and State of New York, have invented a new and Improved Automatic Seal-Trap for Wash-Basins and Water-Closets, of which the following is a full, clear, and exact description.

My invention relates to improvements in automatic seal-traps for wash-basins and water-closets; and it consists in the peculiar construction and arrangement of the parts, as hereinafter more fully set forth, and pointed out in the claims.

Reference is to be had to the accompanying drawings, forming part of this specification, in which similar letters of reference indicate corresponding parts in all the figures.

Figure 1 represents in rear view and partly in section a wash basin or bowl fitted with my improvements. Fig. 2 is a vertical sectional elevation at right angles to Fig. 1; and Fig. 3 is an enlarged detail sectional elevation, specially designed to show the water-inlet and waste or discharge valves and their immediate connections.

The letter *a* represents a wash bowl or basin of the usual or any approved form, and fitted with the discharge plug or stopper *b* and overflow channel or duct *c*, leading from the usual basin-apertures, *d*, to the waste-pipe *e*, through any suitable screw-plug and nipple-connections, *f*, and valve-casing *g*, fitted with a straight-way plug or other suitable valve, *h*, which has connection, by extensions of its stem, with a yoke lever or arm, *i*, carrying a suitably-connected weight, *j*, of sufficient gravity to maintain the automatic closure of the valve *h*, as in Fig. 3, any approved water-seal trap, *k*, being provided between valve *g* and the waste-pipe *e*.

I have here represented the basin *a* as supplied by both hot and cold water from the nozzles or faucets *l l*, through water-inlet pipes *m n*, which connect with the casing or jacket *o* of inlet-valves of peculiar construction, as next described; and as the water-flow to either hot or cold water faucets is controlled by similarly-constructed and like-operating devices, the same description will suffice for either or both the faucets and connections, as follows:

For a convenient and substantial support

for these water-inlet valves and connections, I prefer to employ a rectangular frame, *p*, located along the back of the basin *a*, and secured to the supporting-frame *q* at its base in any suitable manner.

The valve-casing *o* is fitted with the transverse division-wall or partition *r*, which has an annular ring, *s*, surrounding the central aperture for the close-fitting body or central portion, *t*, of the valve *u* to slide in, said apertured partition *r* and valve *u* dividing the casing *o* into an upper chamber, *v*, and a lower chamber, *w*, which connect, respectively, with the pipe *m*, leading to the faucet *l*, and the pipe *n*, leading from the water-supply.

To provide for the economical manufacture of the casing *o*, I propose to make its main body portion in cylindrical form and of uniform diameter throughout, aside from the nipple connections of the pipes *m n*, which nipples *x* may either be cast with or screwed into the main body of the casing *o*, as desired, which construction of the casing enables me to rapidly screw-thread its opposite ends externally or internally for a secure connection with the base-plate of frame *p* by screwing the casing into or over a collar, *y*, formed on or fixed to frame *p* at the bottom, and to receive at its top the screw-cap and stuffing-box *a' b'*, through which the main stem *c'* of valve *u* moves with a water-tight joint. The frame *p* also has a tubular extension, *d'*, centrally of the bore of casing *o*, to receive the lower extension, *c''*, of the stem of valve *u*, which is thus supported above and below for long-continued precision of action in insuring a tight valve-closure for completely shutting off the water-supply from pipe *m*, the coiled spring *e'* below the valve aiding its prompt seating, and the packing *f'* insuring a water-tight joint of the casing *o* with the base *p*, and the valve *u* may or may not be fitted with any approved packing, *g'*, where it seats itself upon the ring *s*.

Above the body portion *t* of valve *u* the head or upper portion of the valve is tapered upward at *t'* to the diameter of the valve-stem *c'*, or thereabout, for gradual inlet and quick cut-off of the water with reference to the opening of the basin discharge-valve *h*, as hereinafter described.

As a means of operating valve *u*, I rigidly

connect its stem c' by a screw-joint or otherwise with the yoke or shackle h' , which has tongues or feathers i' , fitted to slide vertically in ways or grooves j' of a collar or bracket bearing, k' , which is fixed suitably to the side of frame p , so as to guide the shackle h' in alignment with the valve-stem $c' c^2$ as the shackle is moved to open or close the valve u by the rod l' , which is held from lengthwise movement by the collars m' , fixed to the rod above and below the top plate of frame p or other convenient support. The rod l' has a double or triple cut screw-thread, n' , which is fitted in a screw-tapped hole in the head of shackle h' , so that a turning of the rod by its handle o' , located conveniently above the basin a , will cause a quick and positive movement of the valve u in controlling the water-supply.

- 20 With a system of valves and operating devices constructed as above described, I propose to connect the valve h in a manner to automatically open it when water is supplied to the basin a from either faucet or both faucets l , and also to allow of the free discharge of the contents of the basin independently of the operation of the valves u , which I accomplish by means of the levers p' , fulcrumed at q' in rods or supports r' , preferably secured by bolt ends and jam-nuts s' to the top plate of frame p , the levers p' being yoked about the valve-stems c' to bear by their short arms against the lower ends of the traversing shackles h' , and their long arms being attached 35 by the chain or other suitable flexible connections, t' , with the yoke or arm i of the valve h . The flexible connection t' permits the valve h to be opened by drawing upon the rod u' , which connects, by a chain or cord, v^2 , with 40 the valve-arm i , and this rod u' is connected also by the chain w' with the basin-stopper b , for removing the stopper to permit discharge of the contents of basin a simultaneously with the opening of valve h by rod u' , 45 while also allowing the stopper b to be removed by chain w' without drawing upon the rod u' when it is desired to open the valve h by opening the inlet-valves u , or either of them.
- 50 The operation is as follows: When either or both of the handles o' are moved to cause the corresponding shackle, h' , to move downward, its connected valve u will be opened; but as the bearing of lever p' on the lower end of 55 shackle h' is constant, and as the portion t of the valve u forbids inlet of water through the valve until the portion t^2 of valve u passes opposite to or below the lower edge of ring s , the valve h will be opened in advance of the 60 inflow of water to the basin a , so as to prevent the free escape of water through the overflow-apertures d and channel e , and through the valve h and waste-pipe e at such times and without danger of flooding the premises 65 by overflow from the top of the basin a . It will also be noted that the taper of the portion t^2 of the valve permits but a gradually-

increasing inflow of water, thus permitting a considerable increase of opening of the valve h in advance of the full supply from the pipes n , and also affords a quick closure of valve u to cut off the inflow of water from pipe n in advance of the closure of the valve h , which will thus remain open longer than is necessary to pass all the water admitted to the basin a , and in practice it is proposed that the area of opening of discharge-valve h shall exceed the combined areas of the openings of the supply-pipes n or their inlet-valves u . Drawing on the rod u' will open valve h without affecting the water-inlet valves u , and stopper b may be withdrawn either by pulling the rod u' or chain w' directly, as above stated.

It will be understood that the rod u is simply the terminal continuation or handle of the chain v' .

It will be understood that the shackle h' may be grooved, and its bearing k' be tongued for guides to the shackle instead of the reverse arrangement above described, and also that the construction and positive action of the parts of my improvements permit their use in either the vertical position shown, or in the horizontal position, or in intermediate positions, as the necessities of the case shall demand, the connections to the valve h being in any case easily made and operated. Neither do I limit myself to the use of a valve h herein shown, or to the precise arrangement of the details of the apparatus as above described, as these may vary within the scope of my invention, which not only provides against overflows of water, but at the same time effectually seals the basins or water-closets to which they may be applied against the escape of foul air and gases so injurious to health.

It will be observed that the lever p' , which connects at one end with the stem of the inlet-valve, is connected at its outer end with the lever i of the discharge-valve by means of a chain, t' , thus forming therewith a flexible connection. As a result of this connection, the discharge-valve may be operated both in conjunction with the inlet-valve and also independently of the inlet-valve. When the inlet-valve stem is pushed down, the discharge-valve will be opened, as before described, and will automatically close when the inlet-stem is released.

When it is desired to open the discharge-valve independently of the inlet-valve, the rod u is raised, which draws the chain v' and opens the discharge-valve without moving the inlet-valve. On releasing the rod u' the discharge-valve automatically closes. The rod u is simply the handle or upward continuation of the chain v' .

Having thus described my invention, I claim as new and desire to secure by Letters Patent—

1. The two separate flexible connections t' and the rod w' , in combination with the lever i of the automatic discharge-valve, and the lever p' of the inlet-valve stem, as shown and described, whereby the discharge-valve may be

operated either in conjunction with or independently of the inlet-valve, as desired, as set forth.

2. The combination, with the operating-lever of a discharge-valve of a wash-basin or other vessel, of the stem c' of an inlet-valve, provided with a sliding shackle, h' , and a lever, p' , connected at one end to the inlet-valve stem, and secured at its opposite end by a flexible connection to the operating-lever of the discharge-valve, substantially as shown and described.

3. The combination, with the valve h , arranged in the waste-pipe, and the lever i , connected to said valve and carrying a weight, j , on its free end, of the inlet-valve t , valve-stem c' , the sliding nut-shackle h' on the upper end

of the valve-stem, the rod l' , having its lower end screw-threaded, and the lever h' , having its short arm engaging the valve-stem of the inlet-valve, and its long arm connected by a flexible connection with the lever i , substantially as herein shown and described. 20

4. The combination, with the frame p , the guide-bracket k' , provided with the ways j' , the shackle-nut h' , secured to the inlet-valve stem c' , and provided with the tongues i' and the rod l' , of the support r' , the lever p' , the chain t , the lever i , the weight f' , and waste-valve h , substantially as herein shown and described. 25 30
